UNITED STATES PATENT OFFICE.

EDWARD C. MEIER, OF PHOENIXVILLE, PENNSYLVANIA.

1,239,026.

Specification of Letters Patent.

Patented Sept. 4, 1917.

Application filed August 5, 1916. Serial No. 113,213.

BOILER.

To all whom it may concern:

Be it known that I, EDWARD C. MEIER, a citizen of the United States, residing at Phoenixville, in the county of Chester and State of Pennsylvania, have invented certain new and useful Improvements in Boilers, of which the following is a specification.

My invention consists of improvements in boilers. One object of my invention is to so make the hand holes in boiler sheets and provide them with hand hole plates that the hand hole plates may be quickly and easily inserted or removed and will be extremely durable and efficient in service.

Another object of my invention is to make the hand holes in water leg plates by drilling different sized intersecting holes directly into the boiler sheet, and to make the hand hole plate so that it can be moved through the hole and then positioned so as to entirely cover the hole on the inside of the water leg.

A still further object is to make the hand hole plates of wrought steel and with an integral threaded stem upon which a nut may be turned.

A still further object of my invention is to provide in combination with the plate above described, a clamping plate of sufficient size to engage the outer surface of the boiler sheet, said clamping plate having an offset hole which may be slid over the nut while on the integral stem of the hand hole plate and also having a recess which, after the plate has passed over the nut, may be moved to partially encircle said integral stem, thus not requiring the entire removal of the nut in order to remove the hand hole plate from its position within the boiler sheet.

Another object of my invention is to so shape the hand hole plate that portions thereof will fit the circular recesses formed by the drilling of the plate, and that an inner flange will be provided on said plate, said flange being of such size as to overlap the hole in the plate and form a retaining means and seal.

These objects, and other advantageous ends which will be described hereinafter, I attain in the following manner, reference being had to the accompanying drawings in which

Figure 1 is a fragmentary elevation of a boiler plate or water leg sheet having a hand hole and hand hole plate and securing means.

constructed in accordance with my invention.

Fig. 2 is a view of similar nature to Fig. 1 showing the position assumed by the clamping plate when the latter is either being inserted or removed.

Fig. 3 is a fragmentary elevation of a boiler sheet showing the hole drilled therein.

Fig. 4 is a sectional view taken on the line a—a of Fig. 1.

Fig. 5 is a sectional view taken on the line b—b of Fig. 2, and

Fig. 6 is a view of similar nature to Fig. 1 showing the clamping plate provided with a hexagonal hole to fit over a hexagonal nut in distinction to the square hole and square nut shown in Figs. 1, 2, 4, and 5.

Referring to the drawings, 1 is the outer plate or sheet of the water leg of a boiler, and has a hand hole 2 of the shape clearly shown in Fig. 3. This hole is preferably formed by first drilling two comparatively small holes 3 and 4, and then drilling the large hole 5 so as to intersect the small holes and thereby produce the hand hole 2 in such manner that the large portion of the hole as shown at 6 has intersecting therewith, at positions substantially diametrically opposite each other, recesses 7 and 8.

It will be noted that the dotted portion of the holes 3 represent the portions which are cut away when the large hole 5 is drilled. All of the holes are preferably reamed so as to produce a clean edge surface.

The hand hole plate 9 is provided with a portion 10 which fits within the portion 6 of the hand hole 2, and is also provided with circular lips 11 which fit within the recesses 7 and 8. The rear portion of the plate 9 is provided with an extended flange 12 which entirely covers the hand hole 2, and the width of this flanged portion is such as to be movable through the portion of the hand hole 2 which includes the two recesses 7 and 8, that portion being the widest portion of the hole.

An integral stem 13 projects outwardly from the portion 10, and is screw-threaded at 14. A nut 15 is movable on the screw-threaded part 10 of the stem 13, and this nut is preferably made with dished or recessed outer or inner ends as shown at 16.

A clamping plate 17 is preferably made convex on its outer surface and concave on its inner surface. This clamping plate is

provided with an offset hole 18 having a plurality of sides, the adjacent sides intersecting each other at angles to correspond with the shape of the angular contour of the nut 15. The plate 17 is also provided with a circular recess 19 which intersects the offset hole 18. The intersecting sides of the hole 18 with the recess 19 extend at a slant or in other words intersect the recess 19 at an angle greater than ninety degrees so that after the plate 17 has been slid over the nut 15, the stem 13 may be moved into engagement with the sides of the hole 18 and guided directly into the recess 19, said position being shown in Figs. 1 and 4 of the drawing. When in this position, the outer edge of the clamping plate engages the portion of the sheet 1 which is immediately adjacent said hand hole 2, and when the nut 15 is tightened, the plate 17 acts as resisting means to consequently draw the hand hole plate into its closed position, it being noted that a gasket 20 is interposed between the flanged portion 12 of the plate 9 so as to form a tight seal.

By having the nut 15 recessed and the outer surface of the plate 15 convex, a portion of the convex surface will project within the recess of the nut adjacent it and thereby form a snug sliding fit between the nut and the said convex surface of the clamping plate so that there is no shearing action between the nut and the clamping plate.

When it is desired to remove the hand hole plate, it is merely necessary to slightly turn the nut 15, so that the clamping plate may be slid into the position shown in Figs. 2 and 5 after which the plate may be removed over the nut, and the hand hole plate, by being turned, may be readily removed from the hand hole 2 without entirely removing the nut 15.

This combination of parts is particularly desirable and serviceable since prior to my invention of combining these elements and forming the hand hole in the manner particularly set forth, the formation and coupling of hand hole plates and their securing means was extremely tedious and expensive, and furthermore they were not efficient in operation.

In Fig. 6, the elements above described are identical with the exception that the offset angular hole 21 is hexagonal in shape as is also the nut 22. Other than these differences, the parts are assembled and constructed in the manner described heretofore.

Furthermore, by making the hand hole plate of wrought steel and having the stem formed integral, and including the clamping plate in combination with the specifically formed plate and hole, it is practically impossible for any of the members to fracture or to become dislodged after once being properly inserted.

It will be noted that the concave surface of the clamping plate extends directly into intersecting engagement with the outer surface of the plate 1. With this construction a slight resiliency is formed in said clamping plate to insure a positive clamping of the several parts.

As shown in Figs. 1, 2, 4, and 5, the offset angular opening is arranged diagonally to the center of the clamping plate. In other words, one of the diagonals of the square opening extends directly through the center of the plate and also through the curved opening. By this construction more metal is secured adjacent the curved opening than if the sides of the square opening were arranged parallel and at right angles to a line passing through the center of the clamping plate. The additional metal thus secured forms a positive bearing for the nut and the corners of the off-set opening are sufficiently rounded so as to prevent shear.

In some instances in making the hand hole 2 as illustrated in Fig. 3, I first make the large hole 5 either by punching it slightly smaller than the desired hole and afterward reaming it to full size, or by boring this hole out to the full size and afterward forming the smaller recesses 7 and 8 by means of a jig.

Furthermore, it will be noted that the circular lips 11, which fit within the recesses 7 and 8, keep the hand hole plates from turning when the nut is being tightened and thus prevents the tearing of the gaskets.

It will be further noted that the nut 15 is recessed both on its inner and outer surface. These recesses protect the threads in the nuts and prevent the threads from becoming "up-set" or from cutting which would happen if the threads bore directly against the convex surface of the plate 17.

Furthermore, by having the nut recessed as shown at 16 to conform to the curvature of the convex surface of the plate 17 adjacent the center of the latter, the construction is such as to compel the yoke to come to a central position with respect to the nut and the stem of the hand hole plate.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

1. The combination of a boiler plate having a hand hole, a hand hole plate having a flanged portion forming a covering for

the hole and engaging the inner surface of the plate adjacent the hole, an integral stem on said hand hole plate, a nut on said stem, a clamping plate having an off-set hole movable over said nut, said clamping plate also having a recess intersecting said hole and movable over said stem behind the nut, said hole having sides in slanting intersection with the recess to guide the stem directly into the latter, said clamping plate having a portion in engagement with the outer surface of the boiler plate and being engaged by the nut, substantially as described. 20
5 12. The combination of a boiler plate having a hand hole, a hand hole plate having a flanged portion forming a covering for the hole and engaging the inner surface of the plate adjacent the hole, a threaded stem on said hand hole plate, a nut on said stem, 25
15 a clamping plate having an off-set hole movable over said nut, said clamping plate also having an intersecting recess movable over said stem behind the nut, said clamping plate having a portion in engagement with the outer surface of the plate and being engaged by the nut, substantially as described. 30

In testimony whereof I have signed my name to this specification in the presence of two subscribing witnesses.

EDWARD C. MEIER.
